UNITED STATES PATENT OFFICE.

WILLIAM FOWLER, JR., OF NEW YORK, N. Y.

DESIGN FOR A PAN.

SPECIFICATION forming part of Design No. 25,131, dated February 4, 1896.

Application filed September 26, 1895. Serial No. 563,798. Term of patent 9 years.

To all whom it may concern:

Be it known that I, WILLIAM FOWLER, Jr., a citizen of the United States, residing at New York, in the county of New York, State of New York, have invented and produced a new and original Design for Pans, and to that class thereof known as "bake-pans," such as are employed for baking beans and other purposes, of which the following is a specification, reference being had to the accompanying drawings, forming a part thereof, in which—

Figure 1 is a plan view of a pan showing my design, and Fig. 2 a transverse vertical section thereof, these two views being deemed necessary to fully illustrate my design.

The leading feature of my design comprises the annular rim or flange A, which is formed around the top of the pan and extends in a horizontal plane therefrom, the pan proper, 20 which is shown at B, being provided with a bottom C, and the side walls of the pan being conical in form or inclined from the bottom upwardly and outwardly.

The bottom C of the pan is also circular in 25 form and the plane thereof is parallel with the

plane of the flange or rim A, and the upper and lower surfaces of the flange or rim are preferably smooth and regular in form; as are also the outer and inner surfaces and bottom of the pan, and when thus formed and when viewed from the top in plan the lines formed by the various parts thereof, including the flange or rim A, the side walls B, and the bottom C, are all circular and regular lines, and said circular lines are practically at equal distances from each other.

Having fully described my new and original design, I claim and desire to secure by Letters Patent—

The design for a pan substantially as herein shown and described.

In testimony that I claim the foregoing as my invention I have signed my name, in the presence of the two witnesses, this 23d day of September, 1895.

WILLIAM FOWLER, JR.
